UNITED STATES PATENT OFFICE.

BERNARD C. LAUTH, OF PHILADELPHIA, PENNSYLVANIA.

HEARTH - FURNACE FOR METALLURGICAL OPERATIONS.

SPECIFICATION forming part of Letters Patent No. 434,715, dated August 19, 1890.

Application filed February 5, 1890. Serial No. 339,252. (No model.) Patented in Canada January 21, 1890, No. 33,464.

To all whom it may concern:

Be it known that I, BERNARD CHARLES LAUTH, a citizen of the United States, residing at Philadelphia, in the county of Philadelphia and State of Pennsylvania, have invented new and useful Improvements in Hearth-Furnaces for Metallurgical Operations, (for which I have received Letters Patent in Canada, dated January 21, 1890, No. 33,464); and I do hereby declare the following to be a full, clear, and exact description of said invention, reference being had to the accompanying drawings, and to the letters of reference marked thereon, which form part of this specification.

My invention relates to improvements in furnaces for heating or melting iron or steel, and for metallurgical operations generally.

The object of my invention is to provide a furnace which will be comparatively cheap in construction and which can be operated at the minimum cost in fuel; and to this end my invention consists in placing the coal-burning furnace at each end of the working-hearth, re-enforcing the flame or fires in the coal-burning furnaces by jets or currents of producer-gas, and finally carrying the waste products of combustion off through a stack located at the working-chamber.

Figure 1 is a longitudinal vertical sectional view of my improved furnace. Fig. 2 is a top or plan view, partly in section. Fig. 3 is a transverse vertical sectional view taken on the line *x x* of Fig. 1. Fig. 4 is a transverse vertical view taken on the line *y y* of Fig. 1.

A indicates the working or heating chamber of the furnace, and *B* the hearth, which gradually slopes from each end of the heating-chamber toward the center, said hearth being supported on a suitable bed of masonry. The side and end walls of the entire furnace are braced by suitable longitudinal and vertical bars and rods in a manner well known to structures of this kind, and the working-doors of the heating-chamber are provided with suitable devices by which they can be readily opened and closed by the operator.

C is a flue leading from the central portion of the working-chamber to a suitable stack *C'*.

D D are the furnaces proper located at each end of the heating or working chamber and communicating therewith by suitable port or ports *E*, located over the bridge-wall *F*. The furnace *D* may be of any approved construction, provided with the usual grate-bars, doors, and ash-pits.

G are chambers built at the ends of the furnaces *D*, in which are located the pipes *H*, through which gas is supplied from the producer to the point of combustion at the bridge-wall. The gas from the producer is supplied to the pipes *H* in the chambers *G* through the pipes *I*, the pipes *H* being coiled in the chamber *G*, so as to present as much heated surface as possible to the gas passing therethrough. The pipes *H* communicate with the pipe or drums *K* at or near their central portions, while the ends of said drums are bent inward at *L* and communicate with the flues *L*, formed in the side walls of the furnace.

M are openings formed in the end walls of the furnaces, which allow a portion of the heated gases and flame to enter the chamber *G* and heat the gases in the drums *K*, the unconsumed gases and products of combustion in the chamber *G* being carried into the flues *L* by the jets of heated gases from the drums *K*, where they are mingled with said gases and carried forward to mingle with the gases and products of combustion arising from the burning fuel from the furnaces *D*, just over the bridge-wall, where a complete combustion of all the gases is effected.

What I claim, and desire to secure by Letters Patent, is—

A furnace for metallurgical operations, consisting of a heating or working chamber having a fire-box at each end thereof, supplemental chambers located outside the fire-boxes, flues in the walls of each fire-box communicating with the supplemental chambers and with the heating-chamber at the bridge-wall thereof, openings in the end walls of the fire-boxes forming communications between them and the supplemental chambers, and gas-supply pipes located in the supplemental chambers and opening into the side flues, substantially as described, whereby a portion

of the products of combustion from the firebox is caused to pass into the supplemental chamber to heat the gas in the pipes therein and to mingle with the gas delivered from the pipes in the flues and the mingled products passed to the working-chamber, as set forth.

In testimony whereof I affix my signature in the presence of two subscribing witnesses.

BERNARD C. LAUTH.

Witnesses:

L. W. SINSABAUGH,
H. M. STERLING.
